UNITED STATES PATENT OFFICE.

JAMES F. BOWSER, OF OAK RIDGE, PENNSYLVANIA.

STOVE.

No. 906,375.

Specification of Letters Patent.

Patented Dec. 8, 1908.

Application filed June 16, 1908. Serial No. 438,850.

To all whom it may concern:

Be it known that I, JAMES F. BOWSER, a citizen of the United States, residing at Oak Ridge, in the county of Armstrong and 5 State of Pennsylvania, have invented a new and useful Stove; and I do hereby declare the following to be a full, clear, and exact description of the invention, such as will enable others skilled in the art to which it app- 10 pertains to make and use the same.

This invention relates to cooking stoves and ranges and it has for its object to provide improved ventilating means for doing away with the annoyance caused by escap- 15 ing steam, fumes and odors when cooking is in progress, as well as that caused by escap- ing smoke when the lids are raised from the stove.

A further object of the invention is to util- 20 ize the steam and hot air rising from the stove for the purpose of maintaining and promoting combustion in lieu of the cold air usually admitted to the ash-pit below the grate through suitable draft openings.

Still further objects of the invention are 25 to simplify and improve the construction and operation of this class of devices.

With these and other ends in view, which 30 will readily appear as the nature of the in- vention is better understood, the same con- sists in the improved construction and novel arrangement and combination of parts which will be hereinafter fully described and par- ticularly pointed out in the claims.

In the accompanying drawings has been 35 illustrated a simple and preferred form of the invention; it being, however, understood that no limitation is necessarily made to the precise structural details herein exhibited, 40 but that changes, alterations and modifica- tions within the scope of the invention may be resorted to when desired.

In the drawings—Figure 1 is a front ele- 45 vation of a cooking range constructed in ac- cordance with the invention, a part having been broken away for the purpose of showing the construction more clearly. Fig. 2 is a rear elevation, partly in section. Fig. 3 is a vertical sectional detail view taken on the plane indicated by the line 3—3, in Fig. 1. Fig. 4 is a horizontal sectional detail view taken on the plane indicated by the line 50 4—4, in Fig. 2. Fig. 5 is a vertical sec- tional view taken on the plane indicated by the line 5—5, in Fig. 2.

Corresponding parts in the several figures are denoted by like characters of reference.

The range A which has been selected for illustration is, in the main, of ordinary conventional construction, being equipped with 60 an upwardly-extending back plate 5 and side plates or brackets 6, 6 supporting a hot closet 7. The body of the range is constructed with the usual fire-box 8 ash-pit 9 and oven 10, the latter being surrounded by 65 flues through which the products of combustion pass to the smoke-pipe 11 which latter is extended through the hot closet. The top of the range is equipped with the cus- 70

tomary lids or covers 12. Connected with the top of the hot closet, and extending in front of the latter, is a hood 13 which extends the full width of the range. A flue 14 extends diagonally through the hot closet, below the top of the latter, 75 the front end of said flue having an aperture 15 communicating with the hood 13. The rear end of the flue 14 communicates with the upper end of a vertical flue 16, disposed adjacent to the back plate 5, and the lower 80 end of the flue 16 communicates with the upper end of a flue or duct 17 placed adjac- ent to the rear side of the body of the stove or range. The parts 16 and 17 may con- 85 stitute a single integral flue, but for con- venience it is preferred to make it in two parts, as shown. The flue-section 17 is pro- vided near its upper end with an opening or aperture 18 having a door or closure 19, and a damper 20 is arranged in said flue- 90 section directly above the opening 18. The lower end of the flue-section 17 communi- cates with the ash-pit 9 through an opening 21; the lower extremity of said flue-sec- 95 tion 17 being obstructed by a permanent closure 22.

In practice, it will be readily seen that steam and fumes rising from cooking vessels upon the stove, as well as smoke escaping through cracks, or when the stove doors or 100 lids are opened, will be intercepted by the hood 13, where a draft or suction is created from the fire-box and ash-pit through the flues 17, 16 and 14; and such steam and smoke, together with the hot air rising from the stove will be conducted through the flues 14, 16 and 17 to the ash-pit from whence it 105 is discharged into the fire-box where combustion will thus be maintained and pro- moted much more efficiently and satisfac- 110

torily than by the cold air usually supplied through draft-openings in the front part of the stove. Such draft-openings are dispensed with by my invention, and danger 5 of hot coals dropping upon the floor through such openings, which is a frequent cause of disastrous fires will thus be avoided.

The draft may be thoroughly regulated by means of the damper 20; and the door 19 10 may be used to further regulate the draft by the admission of cold air, when desired.

Having thus described the invention, what is claimed is—

1. A stove or range, a hot closet supported above the same, a hood adjacent to the hot closet, a flue extending through the hot closet and communicating at one end with the hood, and a duct extending from the

other end of the flue to the ash-pit of the stove.

2. A stove or range having a fire-box and ash-pit tightly closed at their front ends, a hot closet supported above the stove, a hood adjacent to the hot closet, and a flue extending from the hood through the hot 20 closet and thence downwardly to the ash-pit, said flue being provided with an opening to the outer air, a closure for said opening, and a damper adjacent to the latter.

In testimony whereof I have signed my 30 name to this specification in the presence of two subscribing witnesses.

JAMES F. BOWSER.
